UNITED STATES PATENT OFFICE.

EDWIN NORTON, OF MAYWOOD, ILLINOIS, ASSIGNOR TO HIMSELF, AND
OLIVER W. NORTON, OF CHICAGO, ILLINOIS.

SHIPPING BOX OR PACKAGE.

SPECIFICATION forming part of Letters Patent No. 602,469, dated April 19, 1898.

Application filed May 22, 1897. Serial No. 637,677. (No model.)

To all whom it may concern:

Be it known that I, EDWIN NORTON, a citizen of the United States, residing in Maywood, in the county of Cook and State of Illinois, 5 have invented a new and useful Improvement in Shipping Boxes or Packages, of which the following is a specification.

My invention relates to improvements in shipping boxes or packages.

10 The object of my invention is to provide a shipping-box of a simple, strong, and durable construction that may be cheaply manufactured, that may be light in weight, so as to save freight, that will serve to preserve goods 15 liable to deterioration or injury by exposure to the air or to tainting by contact with wood, and which may be easily and conveniently opened without injury to the box or package, so that the shipping-package itself may serve 20 as a receptacle for the goods while they are being consumed or sold at retail.

To produce a shipping box or package that will in itself alone unite all the features necessary to accomplish at the same time all these 25 results or perform the function necessary to meet all these different requirements or conditions, and thus make a practicable and successful shipping box or package, I construct it as follows, and herein my invention consists.

30 The body, bottom, and cover of the box comprise each a tin-plate or sheet-metal interior and a wood-veneer exterior, and reinforcing-strips of wood, preferably united at the corners by metal clips, surround the body 35 at its upper and lower ends and firmly clamp the wood-veneer body between the sheet-metal body and said wood reinforcing-strips by nails or fastenings inserted through them. Reinforcing-strips of wood surrounding the 40 cover at the margins thereof serve to hold the wood-veneer cover smooth or in a flat plane and in close contact with the sheet-metal cover and to bind the two firmly together. The combined cover thus formed is given a 45 firm seat at its margin on the upper end of the combined wood-veneer and sheet-metal body, while the reinforcing-strips of wood projecting above the end of the wood body form a seat or protective receptacle for the 50 edges of the cover and relieve the hinges and fastenings uniting the cover and body from

any wrenching or prying strain to which the cover might be subjected in shipment or handling of the package; and the reinforcing-strips of wood at the lower end of the body, 55 projecting below the end of wood-veneer body and flush with the lower face of wood-veneer bottom, thus form a seat for the rim or outer edge of the combined sheet-metal and wood-veneer bottom and protect and strengthen the 60 lower end of the sheet-metal body, which is folded over the edge or rim of the combined wood-veneer and sheet-metal bottom to secure the bottom to the body. The nature of my invention will be more fully understood by 65 reference to the accompanying drawings, forming a part of this specification.

In the drawings similar letters of reference indicate like parts in the several figures.

In the drawings, Figure 1 is a plan view, 70 and Fig. 2 a side elevation, of a shipping box or package embodying my invention. Figs. 3 and 4 are enlarged detail sectional views on lines 3 3 and 4 4, respectively, of Fig. 1; and Figs. 5 and 6 are enlarged detail sectional 75 views on lines 5 5 and 6 6, respectively, of Fig. 2.

In the drawings, A represents the interior sheet-metal body of the box, the meeting ends or edges of the sheets of which the body is 80 composed being united together, preferably at the corners of the box, by interlocked or folded seams a.

A' is the exterior wood-veneer body of the box, the wood-veneer sheets composing the 85 body being placed with the grain of the wood upright.

B is the sheet-metal bottom, and B' the wood-veneer bottom, of the box.

C is the sheet-metal cover, and C' the wood- 90 veneer cover, of the box.

D D are reinforcing-strips of wood surrounding the body of the box at the lower end thereof, and D' are similar wood strips surrounding the body of the box at the upper 95 end thereof, and D² are reinforcing-strips secured to the cover at the rim or margins thereof.

The wood-veneer bottom B' is secured to the sheet-metal bottom B by folding the rim or 100 edge b of the sheet-metal bottom over and around the rim or edge of the wood-veneer

bottom, and the combined sheet-metal and wood-veneer bottom thus formed is firmly secured to the sheet-metal body A of the box by the folded lower end or edge a' of the sheet-metal body, which embraces the rim or edge of the combined sheet-metal and wood-veneer bottom, as will be readily understood by reference to Fig. 6, and the lower edge d of the wood reinforcing-strips D, which project below the lower end of the wood-veneer body A' and flush with the lower surface of the combined bottom, form a seat for the rim or edge of the combined bottom to fit or abut against, thus protecting the same and materially strengthening the folded end or rim a' of the sheet-metal body by which the combined bottom is secured to the body of the box. The wood-veneer body A' abuts at its lower end against the rim or margin of the combined bottom B B', which extends out flush with the outer surface of the wood-veneer body, the lower end of the sheet-metal body having a lateral flange a^2 extending across the end of the wood-veneer body, as will be seen from Fig. 6. The wood-veneer body A' is firmly and rigidly clamped between the sheet-metal body A and the wood reinforcing-strips D and D' by nails or other fastenings d' , extending through these three parts and firmly clenched, as illustrated in the drawings. The wood strips D D are firmly secured together by metal clips or angle-pieces d^2 at their corners, and similar clips d^3 are employed at the corners of the strips D' D'. The nails or fastenings d' , securing the clips in place, are inserted through the sheet-metal and wood-veneer bodies as well as the clips d^2 and strips D and D'. By this means it will be seen that the wood-veneer and sheet-metal bodies are firmly united together, so that each reinforces the other, and that the combined body is greatly strengthened in the direction transverse to the grain of the wood-veneer body by the wood strips D D', extending transverse to the grain of the wood veneer, and that the whole is braced and strengthened by the bottom B B', while the bottom itself is not only firmly and rigidly secured to the body, but is also greatly strengthened at its rim by the manner in which it is combined with the sheet-metal and wood-veneer bodies and with the surrounding wood reinforcing-strips D.

The sheet-metal body A at its upper end is furnished with a lateral flange or offset a^2 , extending across the end or thickness of the wood-veneer body, and an upright flange a^3 , having its edge a^4 folded down upon itself to make a smooth finish. The rim or marginal edge c of the sheet-metal cover C is folded over the rim or margin of the wood-veneer cover C', thus securing the sheet-metal and wood-veneer covers together.

The upper edge of the reinforcing-strips D' at the upper end of the body of the box projects above the upper end of the wood-veneer body A, so that the upper edge of the strips D' are flush with the upper surface of

the wood-veneer cover C. The reinforcing-strips D' thus form a seat for the edge of the rim of the combined covers to fit or abut against. This materially relieves the hinges and fastenings by which the cover is secured to the body of the box from all lateral or wrenching strains. The reinforcing-strips D², surrounding the combined cover at the margin thereof, are secured thereto by nails or fastenings d' , which extend through the sheet-metal cover C, the wood-veneer cover C', and the strips D², and are firmly clenched, as illustrated. The metal hinge-straps F, which are secured to the body of the box, are furnished with offsets f , extending across the end of the wood-veneer body A', and are firmly secured in place between the sheet-metal body A and the wood-veneer body A' by soldering or by nails or fastenings d' , or both. The metal hinge-straps F', which are secured to the combined cover C C', fit between the reinforcing-strips D² and the wood-veneer cover C' and are secured in place by the nails or fastenings d' , extending through the same. To firmly lock or secure the front edge of the combined cover in place, I secure a fastening-strap G by nails or screws g to the reinforcing-strip D², and provide this metal fastening-strip G with a fastening-strap G', which is hinged thereto, as illustrated in Figs. 1, 2, and 4. The fastening-strap G' is provided with a hole through which a screw g' may be inserted, the threaded end of which engages a nut g^2 , soldered to the sheet-metal body A, near the upper end thereof. The combined cover C C' thus fits and rests directly upon the upper end of the combined body A A', so that the cover is firmly supported, thus enabling the shipping boxes or packages to be piled one on top of another, as the hinges and fastenings are entirely relieved from strain or pressure in this direction, while at the same time the reinforcing-strips surrounding the combined body at its upper end forms a seat for the edges of the combined cover to abut against and relieves the hinges and fastenings from any lateral or side strain.

I claim—

1. A shipping box or package comprising in combination the following parts: a sheet-metal body and a wood-veneer body, the sheet-metal body having lateral flanges or offsets extending across the end or thickness of the wood-veneer body, a sheet-metal bottom and a wood-veneer bottom, the rim of the sheet-metal bottom being folded over and around the edge of the wood-veneer bottom, and the lower end of the sheet-metal body being folded over and around the combined sheet-metal and wood-veneer bottom to secure the body and bottom together, the wood reinforcing-strips D D' secured together at the corners by metal clips and surrounding the body at its upper and lower ends and provided with nails or fastenings extending through and securing firmly together said sheet-metal body and wood-veneer body and

reinforcing-strips, the lower edge of said reinforcing-strips at the lower end of the body projecting below the lower end of the wood-veneer body to form a seat, protection or 5 abutment for the marginal edge of the combined bottom, and a sheet-metal cover and a wood-veneer cover furnished with marginal wood reinforcing-strips D^2 , the rim of said sheet-metal cover being folded over and embracing the rim of said wood-veneer cover, and nails or fastenings extending through and uniting said wood-veneer cover, sheet-metal cover and wood reinforcing-strips D^2 , the upper edge of said upper reinforcing-strips D' on the body projecting above the upper end of said wood-veneer body and forming a seat or abutment for the edges of the combined cover to fit against, and hinge-straps and fastening-straps secured to the 15 combined cover and combined body, substantially as specified.

2. In a shipping box or package, the combination with a sheet-metal body of a wood-veneer body, reinforcing-strips of wood surrounding the wood-veneer body, and fastenings extending through said strips and sheet-metal and wood-veneer bodies, a wood-veneer bottom and a sheet-metal bottom having its rim folded over the edge of said wood-veneer 25 bottom, the lower end of said sheet-metal body being folded over the rim or edge of the combined bottom, the lower edge of said wood strips at the lower end of the body projecting below the lower end of the wood-veneer body 30 and surrounding the edge of the combined bottom, substantially as specified.

3. In a shipping box or package, the combination with a sheet-metal body of a wood-veneer body, reinforcing-strips of wood surrounding the wood-veneer body, and fastenings extending through said strips and sheet-metal wood-veneer bodies, a sheet-metal cover and wood-veneer cover furnished with reinforcing-strips D^2 , said combined cover fitting 40 and resting at its margin on the end of said wood-veneer body, and the reinforcing wood strips at the upper end of the body projecting above the upper end of the wood-veneer body to form a seat and protection for the edges of the cover, substantially as specified. 45

50 4. In a shipping box or package, the com-

bination with a sheet-metal body of a wood-veneer body, reinforcing-strips of wood surrounding the wood-veneer body, and fastenings extending through said strips and sheet-metal wood-veneer bodies, a sheet-metal cover and wood-veneer cover furnished with reinforcing-strips D^2 , said combined cover fitting and resting at its margin on the end of said wood-veneer body, and the reinforcing wood strips at the upper end of the body projecting above the upper end of the wood-veneer body to form a seat and protection for the edges of the cover, hinge-straps F secured to the reinforcing-strips at the upper end of the body, and hinge-straps F' secured to the reinforcing-strips on the cover, substantially as specified. 55

5. In a shipping box or package, the combination with a sheet-metal body of a wood-veneer body, reinforcing-strips of wood surrounding the wood-veneer body, and fastenings extending through said strips and sheet-metal wood-veneer bodies, a sheet-metal cover and wood-veneer cover furnished with reinforcing-strips D^2 , said combined cover fitting and resting at its margin on the end of said wood-veneer body, and the reinforcing wood strips at the upper end of the body projecting above the upper end of the wood-veneer body to form a seat and protection for the edges of the cover, hinge-straps F secured to the reinforcing-strips at the upper end of the body, and hinge-straps F' secured to the reinforcing-strips on the cover, substantially as specified. 60

65 6. A shipping-box comprising the following parts, a sheet-metal body A , wood-veneer body A' , sheet-metal bottom B , wood-veneer bottom B' , sheet-metal cover C , wood-veneer cover C' , wood reinforcing-strips D D' D^2 , hinge-straps F F' , fastening-straps G G' , screws g and nuts g^2 , all constructed, combined and coöperating substantially as specified. 70
